CLAIM

The ornamental design for a wig head mannequin, as shown and described.

DESCRIPTION

FIG. 1 is a front, right, and top perspective view of a wig head mannequin, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a view of the wig head mannequin showing how the head may appear with a wig placed thereon, and with a hair dryer inserted in the front opening.

The broken lines shown in the drawings are included for the purpose of illustrating portions of the wig head mannequin that form no part of the claimed design.
